RULE ATTACHMENT FOR DRAFTING MACHINES

David B. Bogan, 7303 Paso Robles Ave.,
Van Nuys, Calif. 91406

Filed Nov. 29, 1967, Ser. No. 9,578

Term of patent 14 years

(Cl. D52—6)

FIGURE 1 is a top plan view of the rule attachment for drafting machines showing my new design;

FIGURE 2 is an enlarged top plan view thereof showing more clearly and accurately the details of the rule attachment;

FIGURE 3 is a rear elevational view thereof;

FIGURE 4 is a front elevational view thereof;

FIGURE 5 is an end elevational view thereof; and

FIGURE 6 is a fragmentary view thereof.

The broken line fragmentary showing of a drafting machine in FIGURE 1 is for illustrative purposes only.

I claim:

The ornamental design for a rule attachment for drafting machines, substantially as shown and described.
